[57] CLAIM

The ornamental design for a base for a pig feeder, as shown and described.

DESCRIPTION

FIG. 1 is a perspective view of a base for a pig feeder, showing our new design;

FIG. 2 is a top plan thereof;

FIG. 3 is a side elevational view thereof, the other sides being the same as the sides shown; and

FIG. 4 is an enlarged bottom plan view thereof.

FIG.2.

FIG.1.

FIG.4.

FIG.3.
